[57] CLAIM

The ornamental design for a combined telephone list
finder, writing instrument and note pad holder, as
shown and described.

DESCRIPTION

FIG. 1 is a top front perspective view of a combined
telephone list finder, writing instrument and note pad
holder showing our new design;

FIG. 2 is a top plan view;

FIG. 3 is a front elevational view;

FIG. 4 is a rear elevational view;

FIG. 5 is a right end elevational view;

FIG. 6 is a left end elevational view; and

FIG. 7 is a bottom plan view thereof.

FIG. 1
